SHOESHINE SHIELD

Alfred A. Caputi, Buffalo, N. Y.

Application August 9, 1947, Serial No. 767,701

1 Claim. (CL 36—70)

1

This invention relates to a shoe shine shield. The principal object of the invention is to provide a protective shield which can be readily mounted on a shoe while on the wearer's foot and which will protect the wearer's sock or stocking from being smeared with shoe polish or otherwise soiled while the shoe is being polished.

Another object is to provide such a shoe shine shield which effectively prevents the entrance of shoe polish into the interior of the shoe as well as protecting the wearer's limb immediately above the shoe from being soiled.

Another object is to provide such a shoe shine shield which tends to maintain the polishing devices used such as polishing rags in effective working position on the shoe so that the polishing operation can be readily and efficiently performed.

A further object is to provide such a shoe shine shield which can be readily applied and removed without requiring removal and replacement of the shoe.

Another object is to provide such a shoe shine shield which when mounted in its operative position on the shoe does not cause any discomfort nor interfere with the shoe shining operations.

Another object is to provide such a shoe shine shield which is simple in construction and inexpensive to manufacture.

Other objects and advantages will be apparent from the following description and drawing wherein:

Fig. 1 is a perspective view of one form of shoe shine shield embodying the present invention.

Fig. 2 is a similar view thereof and shows the shield in an operative position on a shoe, the shoe and wearer's ankle being illustrated by broken lines.

Fig. 3 is a vertical transverse sectional view thereof taken on line 3—3, Fig. 2.

Fig. 4 is a top plan view of the shield shown in Fig. 2.

Fig. 5 is a fragmentary vertical sectional view similar to Fig. 3 and showing the distortion of the shield when mounting the same between a shoe and the angle of the wearer thereof.

Fig. 6 is a sectional view similar to Fig. 3 and showing a modified form of the invention.

Fig. 7 is a fragmentary sectional view similar to Fig. 3 and showing another modified form of the invention.

The shoe shine shield embodying the present invention is shown as being adapted to be used in connection with the so-called oxford type shoe although it is to be understood that shields embodying the invention can be employed with other types of shoes.

Referring to Figs. 1—5, the shield is shown as being in the form of a one piece, split, generally

2

elliptically curved body of relatively thin, flexible material such as sheet metal or plastic or other suitable material and including an intermediate sleeve section 10, an integral lower flange 11 and an integral upper flange 12. The lower flange 11 is shown as extending downwardly and outwardly from the lower edge 13 of the intermediate sleeve section 10. The lower edge 13 of this section 10 is curved so as to conform to and follow generally the conventional curvature of the upper edge 14 of the upper structure of an oxford type shoe represented generally by the numeral 15, this upper edge 14 defining the opening through which the foot is inserted into the shoe. The lower flange 12 is also preferably of even width so that the free lower edge of this flange is generally parallel to the lower edge 13 of the intermediate sleeve section 10.

The intermediate sleeve section 10 is shown as extending upwardly and outwardly from its lower edge 13 and terminating in a substantially horizontal upper edge 16. The upper flange 12 is shown as extending laterally and outwardly from this upper edge 16 at a slight upward inclination to the horizontal as best shown in Fig. 3. This laterally extending upper flange 12 is also shown as being of even width so that the free upper edge of this flange is substantially parallel to the upper edge 16 of the intermediate sleeve section 10.

The shield is so formed that normally the adjacent edges 18 of the intermediate sleeve section 10 are relatively far apart when the shield is not mounted in an operative position, as shown in Fig. 1. However, the shield is sufficiently flexible and springy that the adjacent edges can be separated farther apart and brought closer together when applying the shield to a shoe.

Referring to Figs. 2 and 3, it will be seen that the lower flange 11 is adapted to be inserted into the foot opening in the shoe 15 between the ankle 19 and the shoe. When the lower flange 11 of the shield is so inserted the lower edge 13 of the intermediate sleeve section 10 is adjacent and substantially parallel to the upper edge 14 of the shoe. By reason of the flexible and compressed condition of the shield when in operative position on the shoe, it will be seen that the lower flange 11 lays conformably against the inner surface of the shoe adjacent the upper edge 14 thereof and exerts an outward pressure thereagainst thereby providing an effective seal between the shield and shoe to prevent liquid or paste shoe polish and the like from entering the shoe at this point.

In this connection, to further produce an effective seal between the shield and the shoe the lower flange 11 is normally at a greater inclination relative to the vertical than the wall of the shoe adjacent the upper edge 14 thereof so that the flexible shield must be distorted from the full

line position to the broken line thereof shown in Fig. 5 when applying the shield to the shoe. In this manner and by reason of the elastic character of the shield the same urges itself toward the broken line position shown in Fig. 5 and also toward the expanded condition shown in Fig. 1, all of which urges the lower flange 11 into intimate effective sealing engagement with the shoe.

It will thus be seen that the joint between the shield and shoe is effectively sealed so that special care need not be taken in applying polish to the exterior surface of the shoe. Also, the upwardly and outwardly inclined wall of the intermediate sleeve section 10 tends to keep the polishing rag from moving off the surface of the shoe and thereby permits the shoe to be shined more quickly and without requiring special care to avoid soiling the sock or stocking of the wearer of the shoe. The upper flange 12 serves as a guard rail to prevent the polishing rag from riding off the intermediate sleeve section 10 while the shield is in use.

Referring to Fig. 2 it can be seen that to apply the shield to the shoe at most it is merely necessary to loosen the shoe lace, insert the lower flange 11 and again tighten the lace. However, in many instances the shield can be applied without first loosening the shoe lace. It will also be seen that the shield is positioned on the shoe so that the edges 18 forming the split therein are located adjacent the tongue of the shoe and that adjustment of the shield to the particular shape of the shoe can be accomplished by expanding or contracting the space between the edges 18. Further, when the shield is mounted on the shoe as shown in Figs. 2 and 3, the flared lower flange 11 fits against the inside of the upper structure of the shoe and tends to prevent withdrawal of the shield from the shoe and the flared intermediate sleeve section 10 would have to be itself distorted in order to permit the shield to be inserted deeper into the shoe and hence it will be seen that the shield is effectively held in operative position on the shoe and cannot be casually or accidentally displaced vertically upwardly or downwardly. However, the shield is preferably of such a flexibility that when the shoe has been shined the shield can be pulled upwardly to remove the lower flange 11 from the shoe and the shield spread to enlarge the space between the edges 18 for removing the shield from around the angle.

A modified form of shoe shine shield embodying the present invention is shown in Fig. 6. The shield shown in Fig. 6 is similar to that shown in Figs. 1-5 and hence the same reference characters have been used to indicate like parts, the only difference being the provision of a hook shaped flange 20 which is preferably formed integrally with the shield. This hook shaped flange 20 is shown as formed on the exterior of the shield adjacent the lower edge 13 of the intermediate sleeve section 10 and having a downwardly turned lip which extends continuously around the shield and cooperates with the lower flange 11 to provide a continuous socket or groove to receive the upper edge 14 of the shoe 15. It will thus be seen that shoe polish and the like will be effectively prevented from entering the shoe.

Another modified form of the invention is shown in Fig. 7 wherein the shield illustrated in Figs. 1-5 is shown as provided with a strip 21 of

any suitable absorbent material such as felt or the like. Similar reference characters have been used to indicate like parts. This strip 21 is shown as cemented to the exterior surface of the intermediate sleeve section 10 immediately above the lower edge 13 thereof although any other suitable mode of attaching the strip may be employed. The strip 21 is shown as being so located that when the shield is in its operative position on the shoe the lower edge of this strip 21 abuts against the upper edge 14 of the shoe thereby to form a continuous engagement with the upper edge 14. In this manner excess shoe polish and the like cannot be left standing on the upper edge 14 of the shoe but will be absorbed by the strip 21.

From the foregoing it will be seen that the present invention provides a shoe shine shield which protects the limb of the wearer immediately above the shoe against being soiled during polishing of the shoe; which effectively prevents shoe polish from entering the shoe; which is simple to apply and remove; and which is simple and inexpensive to manufacture.

I claim:

25 A shoe shine shield comprising a split generally elliptically curved one piece body of thin flexible material of substantially uniform thickness throughout and formed to normally assume a shape in which the adjacent edges thereof providing said split are relatively widely spaced apart, said body including a sleeve section flared upwardly and outwardly relative to the vertical and adapted to surround a portion of the limb of the wearer immediately above the shoe, said sleeve section having a lower edge conformably curved to follow the conventional curvature of the upper edge of the upper structure of a shoe defining the foot opening of the shoe, and an integral flange of substantially uniform width extending downwardly and outwardly from said lower edge of said sleeve section and extending continuously therearound, the inclination of said flange relative to the vertical being normally greater than the inclination of said sleeve section and being normally greater than the inclination of said upper structure of the shoe adjacent said foot opening thereof, the juncture between said sleeve section and flange providing a relatively flat but sharply apiced V-shaped indentation in the exterior of said body, said flange being adapted to be inserted substantially its full width between the shoe and foot of the wearer thereof so that the apex of said V-shaped indentation is adjacent said upper edge of the shoe and with said body contracted to narrow the space between said adjacent edges thereof and with said flange forced to assume a greater vertical inclination thus causing said sleeve section to incline farther from the vertical whereby said flange is biased outwardly firmly against the inside of said upper structure of the shoe.

ALFRED A. CAPUTI.
